[57] CLAIM

[] Term: 14 Years

The ornamental design for the external perimetric band for sport shoes, as shown and described.

[21] Appl. No.: 29/082,512

DESCRIPTION

[22] Filed: Jan. 23, 1998

FIG. 1 is a perspective front view of the external perimetric band, showing our design;

[30] Foreign Application Priority Data

FIG. 2 is a side view thereof, taken from one side, showing our new design;

Jul. 25, 1997 [XH] Hague Agreement DM/040 899

FIG. 3 is a side view thereof, taken from the other side,
showing our new design;

[51] LOC (6) Cl. 02-99

FIG. 4 is a front view thereof, showing our new design;

[52] U.S. Cl. D2/946; D2/904; D2/947;
D2/972

FIG. 5 is a rear view thereof, showing our new design;

[58] Field of Search D2/904, 946, 947,
D2/972; 36/113, 114, 115, 25 R, 32 R, 45

FIG. 6 is a view thereof, taken from above, showing our new design; and,

[56] References Cited

FIG. 7 is a view thereof, taken from below, showing our new design.
